GRAVE VAULT

Frank C. Loge, Evansville, Ind.

Application August 3, 1953, Serial No. 371,865

6 Claims. (Cl. 27—35)

1

My invention relates to improvements in grave vaults for burial caskets.

The primary object of my invention is to provide in such vaults an improved base for the hood of the vault, and simplified reliable means for latching the hood of the vault to the base when the hood is lowered over the base.

Another object is to provide in such vaults, means for preventing the sides of the hood from spreading apart while the vault is being carried by pallbearers.

Still another object is to provide in such vaults efficient, durable water- and insect-proof sealing means between the hood and base.

Still another object is to provide for accomplishing the above without appreciably increasing the cost of manufacture of the vault.

Other and subordinate objects, together with the precise nature of my improvements, will become readily apparent when the succeeding description and claims are read with reference to the drawings accompanying and forming part of this specification.

In said drawings:

Figure 1 is a view in perspective of a grave vault embodying my improvements;

Figure 2 is a view in bottom plan of the hood;

Figure 3 is an enlarged fragmentary view in bottom plan, partly broken away, of the base;

Figure 4 is an enlarged view in vertical transverse section taken on the line 4—4 of Figure 1;

Figure 5 is a further enlarged fragmentary view in vertical transverse section taken on the same line as Figure 4; and,

Figure 6 is a fragmentary view in vertical longitudinal section taken on the line 6—6 of Figure 5.

Referring to the drawings by numerals, in the vault 1, with which my improvements are especially concerned, the hood 3, with the exceptions presently noted, is of the usual rectangular open bottom type with side and end walls 5, 7 and handles 9 on plates 11 spaced along the side walls 5 and secured thereto by welding, not shown. According to my invention, the bottom edges of the hood 3 are reinforced on the outside of the hood by metal strips 13 extending along the side and end walls 5, 7 and suitably secured thereto.

The base 15 embodying my improvements is rectangular, hollow, open at its bottom, formed with side, end and top walls, 17, 19, 21, and fits in the bottom of the hood 3 so that said hood 3 may be lowered to slide downwardly over said base 15.

Triangular plates 23 are suitably attached to

2

the corners and bottom of the base 15 to brace the base 15 at its bottom corners, and which act as elevating supports or rests for said base and sustain the entire weight of the vault.

Intermediate the transverse center and ends thereof, the base 15 is provided with a pair of subjacent transverse brace bars 25, 26 suitably secured to the top wall 21 and having downwardly offset, horizontal end portions 27, 28 above the bottom of the triangular plates 23 and which extend outwardly under the side walls 17 of the base 15 and seat thereon at the bottom edges of the side walls 5 of the hood 3, also the bottom edges of the side walls 17 of said base. The brace bars 25, 26, or in other words, the end portions 27, 28, terminate in pairs of laterally spaced upstanding keeper lugs 29, 30 straddling and securing together the bottom edges of the side walls 5, 17 at opposite sides of the base 15 to thereby prevent said side walls 5 from spreading apart outwardly under outward pull thereon when the vault 1 is being carried by the handles 9.

The latching means comprises a pair of latch bolts 31, 33 mounted transversely in the base 15 in pairs and at opposite sides thereof and along side the brace bars 25, 26 to be projected outwardly through apertures 26', 28 in the side walls 5, 17 which apertures register when the hood 3 is seated in the manner described on the end portions 27, 28. The latch bolts 31, 33 are slidably mounted in pairs of spaced guides 35, 37 depending from and welded, as at 39, to pairs of mounting plates 41, 43 suitably secured to the top wall 21 of the base 15 at opposite sides of said base.

Pairs of coil springs 45, 47 on the pairs of latch bolts 31, 33 between the guides 35, 37 of the pairs of guides bear against stop pins 49 in said bolts 31, 33 and urge said bolts outwardly to project the same into locking position, as shown in Figures 3 and 5. Pairs of chains 51, 52 connect the pairs of latch bolts 31, 33 to crank arms 53, 55 on a longitudinal rock shaft 57 mounted in the base 15 and depending lugs 59, 61 on the top wall 21 welded, as at 62, thereto, the arrangement being such that by rocking said shaft 57 in one direction, the chains 51, 53 will retract the latch bolts 31, 33 in opposition to the springs 45, 47 to hold said bolts in unlocking position. A short hand crank 63 on one end of the rock shaft 57 provides for manually rocking the same.

Open bottomed side boxes 65 are provided on the lower portions of the side walls 5 of the hood 3 to cover the outer ends of the latch bolts 31, 33, the keeper lugs 29 and the apertures 26. The sealing means between the hood 3 and

base 15 comprises a rectangular, angle iron frame 67 inside the hood 3 suitably secured to the side and end walls 5, 7 of said hood to provide a horizontal continuous internal flange 69 in the lower portion of the hood 3, and a rectangular, flat sealing frame 71 of resilient rubber suitably secured to the bottom of the flange 69 to seat and be compressed against the top wall 21 under the weight of the hood 3.

The operation of the described invention will be readily understood. With the latch bolts 31, 33 retracted into unlatching position by rocking of the rock shaft 57, in the manner already described, the hood 3 is lowered over the base 15 until the bottom edges of the side walls 5 seat on the end portions 27, 28 of the brace bars 25, 26 and are interposed between the side walls 17 of the base 15 and the outer most keeper lugs of the pairs 29, 30, and the sealing frame 71 seats on the top wall 21 of the base 15. The rock shaft 57 is then released, whereupon, the latch bolts 31, 33 will be projected to enter the apertures 26', 28 to lock the hood 3 down on the base 15 in tightly sealed position.

It is to be noted that the frame 67 serves as a reinforcement holding the bottom part of the hood 3 in shape to provide a perfect seal around the sealing frame 71.

The foregoing will, it is believed, suffice to impart a clear understanding of my invention, without further explanation.

Manifestly, the invention is susceptible of modification, without departing from the inventive concept, and right is herein reserved to such modifications as fall within the scope of the invention as disclosed herein.

Having described my invention, what is claimed as new is:

1. A grave vault comprising a rectangular, hollow open bottom base having side walls and a top wall, an open bottom hood fitting downwardly over said base and having side walls, sealing means in said hood seating on said top wall under the weight of the hood, a pair of subjacent trans-

verse cross bars on said base upon opposite sides of its transverse center having downwardly offset end portions underlying the bottom edges of the side walls of the base and seating thereon the bottom edges of the side walls of the hood, terminal means on said offset portions straddling the bottom edges of the side walls of the base and hood at opposite sides of the vault, and means in said base and the side walls of said hood and base coacting to latch said hood against upward movement relative to said base.

2. A grave vault according to claim 1, said sealing means comprising a lateral rectangular frame rigidly secured to said hood, and a rectangular resilient frame underlying and fixed to said first-named frame.

3. A grave vault according to claim 1, said terminal means comprising pairs of laterally spaced upstanding lugs.

4. A grave vault according to claim 1, said last named means comprising sliding latch bolts in said base spring loaded for projection into latching position, and registering apertures in the side walls of the base and hood for receiving the projected latch bolts.

5. A grave vault according to claim 4, said latch bolts being positioned alongside said bars, and external boxes on the side walls of said hood for hiding said bolts from view.

6. A grave vault according to claim 1, said last means comprising sliding latch bolts in said base spring loaded for projection into latching position, and a rock shaft in said base operatively connected to said bolts to hold the same against projection.
